UNITED STATES PATENT OFFICE.

DONALD G. LITTLE, OF EDGEWOOD, PENNSYLVANIA, ASSIGNOR TO WESTINGHOUSE ELECTRIC & MANUFACTURING COMPANY, A CORPORATION OF PENNSYLVANIA.

TRANSMITTING SYSTEM.

Application filed May 15, 1926. Serial No. 109,277.

My invention relates to transmitting systems, and it has particular reference to radio transmitting systems.

One object of my invention is to provide a 5 radio transmitting system that will radiate a carrier wave having a constant frequency.

Another object of my invention is to provide, in a radio transmitting system having a piezo-electric-crystal control for the oscillation generator, a high-power amplifier that 10 will not oscillate at undesired frequencies.

Another object of my invention is to provide, in the power amplifier portion of a radio transmitting system of the type described, 15 means for preventing feed-back from one unit of the amplifier to a preceding unit.

Another object of my invention is to provide, for the master oscillator tube of a transmitting system of the type described above, 20 means for controlling the amplitude of the oscillations generated.

Another object of my invention is to provide, in a transmitting system of the type described, 25 means for preventing individual amplifier tubes from oscillating at undesired frequencies.

A still further object of my invention is to provide, in a transmitting system of the type described, means for compensating against 30 energy feed-back from the output circuit of an amplifier tube to the input circuit thereof by reason of the inter-element capacities of the tube and the capacity existing between such tube elements and the ground.

Other and more specific objects will be 35 apparent from a consideration of the accompanying drawings, and the following description.

Perhaps one of the most efficient types of 40 radio transmitting systems now in use, is that known as the master-oscillator, power-amplifier type. In the master-oscillator systems, the output of a low-power oscillating thermionic tube is successively amplified in tubes of increasing power capacity, until the 45 amplitude is sufficient for effective radiation.

It has been found advantageous to control the frequency of the first tube by piezo-electric-crystal means, assuring, in this manner, 50 an output at a constant frequency. The crystal-controlled oscillator has one very decided disadvantage, however, being prone to oscillate at a variety of higher harmonics of the fundamental frequency of the crystal.

In my co-pending application, Serial No.

78,115, filed December 29, 1925, I have disclosed and claimed a system for taking advantage of the above-specified peculiarity of crystal-controlled oscillators, in order to transmit on ultra-short wave lengths. -60

It is necessary, when employing a plurality of stages of amplification between the crystal-controlled tube and the antenna, or radiating structure, to entirely eliminate the feed-back of energy from one stage to a preceding 65 stage. To a certain extent, this feed-back is prevented when a system according to the disclosure in my co-pending application is employed, since each stage is tuned to a frequency differing from that of the preceding 70 stage. Nevertheless, when high-power tubes are used, the various elements of which have a large capacity-to-ground, it has been found extremely difficult to so neutralize an amplifier that it will be entirely free from any 75 tendency toward self-oscillation.

My present invention provides means for positively and definitely controlling the generation of oscillations in amplifier circuits. To do this, I use, instead of the usual type 80 of neutralizing condenser, a capacitive device which not only exactly duplicates all the inter-electrode capacities of the tubes employed, but also duplicates the capacity-to-ground of such tubes. Preferably, the device 85 should be evacuated, and provided with three electrodes, and I have found that, by using, as a neutralizing device, a tube of the same type as the tube being neutralized, I can attain substantially perfect results. 90

For a complete understanding of my invention, reference is made to the accompanying drawings, and to the following description.

Figure 1 is a diagrammatic view of the 95 circuits involved in a radio transmitting system arranged according to my invention.

Figure 2 is a diagram illustrating the various tube capacities which I have found it necessary to neutralize, 100

Fig. 3 is a diagram illustrating an alternative method for neutralizing the low-powered, crystal-controlled stage of a radio transmitting system.

Referring specifically to Fig. 1, a master-oscillator tube 1 having a grid 2, a filament 3 and a plate 4, is provided with an input circuit comprising a piezo-electric crystal 5 and a radio frequency choke 6. An oscillating circuit composed of an inductor 7 and a con- 105

denser 8, is connected between the plate 4 and the filament 3, a large condenser 9 being used as a radio-frequency by-pass. Plate potential for the tube is obtained from a 5 battery 10, a portion 12 of the battery 10 also providing grid-bias potential for the master-oscillator tube 1 and the next tube in the series.

A second amplifier tube 13, of considerably 10 higher power than the oscillator tube 1, is provided, this tube being also provided with the usual filament 14, plate 15 and grid 16. The grid 16 is coupled to the output circuit 7, 8 of the oscillator tube 1 through a condenser 17, and is supplied with bias potential 15 from the battery 12 through a radio-frequency choke coil 18.

Plate current for the amplifier tube 13 is supplied from a high-voltage source (not 20 shown) through a radio-frequency choke coil 19.

An oscillating circuit, comprising a plurality of condensers 20 and an inductor 22, is coupled to the plate 15 through a condenser 25 23, and an additional condenser 24 is connected between an intermediate point 25 on the inductor 22 and the filament 14. A connection is also made from the inductor 22, 30 through a neutralizing condenser 26, to the grid 16 of the tube 13, the point 27 of connection to the inductor 22 being so chosen that it will, at all times, be at a potential with respect to the central filament tap 25 which is equal and opposite to that of the point at 35 which the coupling condenser is connected. The purpose of this will be later explained in connection with Fig. 3.

A plurality of high-power amplifier tubes 29 are provided each having a grid 30, a 40 filament 32 and a plate 33. The plates and grids of these power-amplifier tubes are arranged in parallel, the grids being conductively connected to the inductor 22 in the output circuit of the preceding tube 13. The 45 grids 30 of these tubes are also connected to the filaments through a radio-frequency choke 34, a resistor 35 and a keying arrangement 36, which will be described in detail later.

50 An oscillating circuit, comprising a plurality of condensers 37 and an inductor 38, is conductively connected to the plates 33, direct current being fed to the plates through a radio-frequency choke 39. A condenser 40 55 of large capacity is connected between an intermediate point 41 on the inductor 38 and the filament circuit, to serve as a radio-frequency by-pass. A plurality of neutralizing devices 42 are connected between a point 43 60 on the inductor 38 and the grids 30 of the power amplifier tubes 29, in substantially the same manner as is connected the condenser 26 in the preceding stage. These devices 42 are provided with an additional electrode 44, 65 however, which electrode is connected to the

filament circuit for reasons which will be later explained.

The last amplifier preferably comprises a plurality of extremely high-power water-cooled tubes 45, each having a filament 46, 70 plate 47 and grid 48. The plates 47 of these tubes are arranged in parallel, as are also the grids, the latter being connected to the output inductor 38 of the previous stage through a condenser 49, and to the filament 75 circuit through a choke coil 50, a resistor 52, and the keying device 36 previously referred to.

An oscillatory circuit, comprising an inductor 53 and a condenser 54, is provided, care 80 being taken to keep the losses in this circuit as low as possible. The plates 47 of the amplifier tubes 45 are conductively connected to the inductor 53, and the inductor is also coupled to an antenna 55 through a plurality 85 of coupling condensers 56. An intermediate point 57 on the inductor is connected to the filament circuit through a condenser 58. Direct current for the plates of the amplifier tubes 45 passes through an iron-cored surge- 90 choke 59 which prevents high transient potentials from being fed back to the source of plate potential.

A plurality of three-electrode neutralizing devices 60 are connected between a properly chosen point 62 on the inductor 53 and the grids 48, in the same manner that the neutralizing devices 42 are arranged in the preceding amplifier stage.

Filament potential for all the tubes thus 100 far described is supplied from a single source (not shown) which may be either a transformer, a motor generator or a storage battery.

105 Signaling is accomplished by applying to the grids of the amplifier tubes a potential sufficient to cause them to block, or stop oscillating. When it is desired that they oscillate, the contact members 63 and 64 of a relay, or keying device 36, are closed, connecting the 110 grids of the amplifier tubes directly to the filament circuit through the resistors 35 and 52. If it is desired to stop the oscillation, the contact members 64 and 65 are closed, which connects the grids to the filament by way of 115 a circuit which may be traced through the resistors 35 52, the added resistor 66, a secondary 67 of a power transformer 68, and the path between a plate 69 and a filament 70 of a rectifier tube 72. The filament 70 of the 120 rectifier is supplied with potential from the same source used to energize the oscillator and amplifier tubes, and plate potential for the tube is supplied by the power transformer 68, the primary 73 of which may be connected across a 220 volt, 60 cycle supply. The rectifier tube 70 builds up, on condenser 74, a charge with a voltage equal to the maximum voltage obtained across the secondary 67. This voltage is applied to the grids of tubes 130

30 and 45 when relay contacts 64 and 65 are closed, and is sufficient to cause them to completely block.

This blocking cannot be accomplished, however, when high-power, water cooled tubes are used, unless feed-back between stages is absolutely neutralized. Such absolute neutralization is the primary object of my invention, and will now be explained in connection with Fig. 2.

I have established the fact that, not only is it necessary to compensate for the feed-back across the grid-plate path of a tube, but the capacity of the tube elements to ground must also be taken into consideration. To stand up under the extremely high voltages existing between the grid and plate of a power amplifier, the insulation of any neutralizing device must be exceptionally good. Such requirements may be met by an evacuated container having therein a plurality of space-separated electrodes and so designed as to exactly duplicate the capacity characteristics of the amplifier tube with which it is to be used.

In Fig. 2, I have illustrated diagrammatically, the various tube capacities that must be compensated. A thermionic device 80, having a filament 81, a grid 82, and a plate 83, has a certain definite capacity between the grid and plate, represented by a condenser 84.

The grid-to-filament capacity is represented by a condenser 85, the grid-to-ground capacity is represented by another condenser 86, while the filament-to-ground capacity is represented by a condenser 87. The plate also has a definite capacity with reference to the filament, which is represented by a condenser 88, and the plate to ground capacity is represented by another condenser 89. All of these capacities must be duplicated in the neutralizing device, and, for that reason, I have shown such devices as equivalent to thermionic tubes in the system illustrated in Fig. 1.

In practicing my invention, I have actually used thermionic tubes as neutralizing devices, and have obtained very excellent results therewith.

In the operation of a radio transmitting system, such as is shown in Fig. 1, the output circuit of the master-oscillator tube is tuned to the frequency of the piezo-electric crystal. Succeeding output circuits may be tuned to this same frequency, or to successively higher harmonics thereof, as explained in my co-pending application, Serial No. 78,115. The harmonic method is perhaps the better of the two, since the feed-back between stages is minimized, and the amplifier is not so prone to oscillate spontaneously. By repeated amplification, a circulatory current of very large amplitude is made to flow in the last output, or "tank" circuit, as it is sometimes known in the art. By coupling this tank cir-

cuit to the radiating device through either a condenser or a properly designed choke coil, a substantially constant frequency may be radiated.

All tendency toward oscillations in the power amplifier circuits is neutralized by the devices 60, since the capacities through which feed-back takes place are exactly compensated. The system will, therefore, radiate no power when the amplifier tubes are blocked, even though the master-oscillator tube continues oscillating.

In certain cases it may be desirable to control the amplitude of oscillations generated by the master oscillator, without altering either filament or plate potential, or changing the grid bias. Inasmuch as this tube oscillates solely by virtue of the capacity coupling through the grid-plate path, if the effectiveness of this coupling is changed the amplitude of the oscillations will be altered.

In Fig. 3, I have illustrated diagrammatically a preferred circuit for the control of oscillations in the master-oscillator tube, corresponding to the tube in Fig. 1. A thermionic tube 90, having a filament 91, a grid 92 and a plate 93, is provided with an input circuit comprising a piezo-electric crystal 94 and a radio-frequency choke coil 95. The filament 91 is supplied with power from a source 96, while a source 97 supplies the proper grid bias potential, and plate power is supplied from another source 98.

An oscillatory circuit, comprising an inductor 99 shunted by a condenser 100, is arranged to be connected to the plate 93 by a conductor 102, and to the positive pole of the source 98 by another conductor 103. Connected between a point 104 on the inductor 99 and the grid 92, is a small variable condenser 105. This type of circuit tends to oscillate at a frequency determined by the crystal, the feed-back necessary to sustain oscillations taking place through the grid-plate capacity of the tube. By so choosing the point 104 on the inductor 99 to which is connected the neutralizing condenser that it will always be at a potential equal to, but opposite in phase to the point on the inductor 99 to which the plate is connected, it is possible to impress on the grid of the tube an amount of energy sufficient to completely stop oscillations. By varying the location on the inductor of the connection from the neutralizing condenser, and, by varying the size of the condenser, I am enabled to accurately control the amplitude of oscillations generated.

By my invention, I am enabled to construct a master-oscillator, power-amplifier, radio-transmitting system that has an output at a substantially constant frequency. By reason of the perfect neutralization, I am enabled to obtain, with my three-electrode vacuum devices, a transmitting system

equipped therewith which will not radiate an appreciable amount of energy during spacing periods. No detrimental harmonics are present in the radiated wave, thus minimizing, to a considerable degree, interference with other stations.

Although I have illustrated and described herein certain specific embodiments of my invention, I am fully aware that many other modifications will suggest themselves to those skilled in the art. My invention is accordingly not to be limited except in so far as is necessitated by the prior art and as indicated by the appended claim.

15 I claim as my invention:

In an amplifying system, an input circuit, an output circuit, a number of vacuum tubes each having a hot cathode, a control electrode and an anode, said cathodes being connected together, to a point of said input circuit and to a point of said output circuit, said control electrodes being connected together and to a different point of said input circuit, said anodes being connected together and to 20 a point in said output circuit at one side of the connection thereof to said cathodes, and a

like number of evacuated devices each having three cold electrodes similar in inter-electrode capacities to the respective inter-electrode capacities of the corresponding electrodes of 30 said vacuum tubes, the electrodes corresponding to said hot cathodes being connected together and to the same points of the input and output circuits respectively as said cathodes, the electrodes of said evacuated 35 devices corresponding to said control electrodes being connected together and to the same point of said input circuit as said control electrodes and the electrodes of said evacuated devices corresponding to said anodes 40 being connected together and to a point of the output circuit at the other side of said connection thereof to said cathodes, whereby the inter-electrode capacity of the evacuated devices is suitably connected to act as a neutralizing capacity for the inter-electrode capacity of the vacuum tubes.

In testimony wherof, I have hereunto subscribed my name this 26th day of April, 1926.

DONALD G. LITTLE.
